[57] CLAIM

The ornamental design for a pattern for beauty care implement, as shown and described.

DESCRIPTION

FIG. 1 is a perspective view of a pattern for beauty care implement showing my new design, the beauty care instrument shown in broken lines for clarity of disclosure;

FIG. 2 is a top plan view thereof;

FIG. 3 is a side elevation thereof;

FIG. 4 is an end elevation thereof, the other end being a mirror image;

FIG. 5 is a fragmentary view of a second embodiment of FIG. 1, on an enlarged scale;

FIG. 6 is a fragmentary view of a third embodiment of FIG. 1, on an enlarged scale; and,

FIG. 7 is a fragmentary view of a fourth embodiment of FIG. 1, on an enlarged scale.
